UNITED STATES PATENT OFFICE.

HARRY A. DOUGLAS, OF BRONSON, MICHIGAN.

INTERNAL-COMBUSTION ENGINE.

Application filed December 30, 1919. Serial No. 343,415.

To all whom it may concern:

Be it known that I, HARRY A. DOUGLAS, citizen of the United States, residing at Bronson, in the county of Branch and State 5 of Michigan, have invented a certain new and useful Improvement in Internal-Combustion Engines, of which the following is a full, clear, concise, and exact description.

My invention relates to internal combustion engines and has for its object the provision of improved valving mechanism requiring limited movement of the valves which are operated constantly to open and close the ports controlled by the valves 10 whereby back pressure is constantly relieved on return movement of the piston and gas is constantly admitted to the compression space on intake movement of the piston. The valve structure that controls the admission 15 and exhaust ports is preferably unitary mechanism in order that the valves may have a fixed relation to each other which corresponds to the fixed relationship of the ports controlled thereby. This unitary valve mechanism is normally at rest but is given sudden movement when its function is to be performed in order that the alternative adjustments thereof may be constantly effective rather than gradually effective.

My invention is of particular service when employed in an internal combustion hydro-carbon engine that contains a multiplicity of units, each unit being a complete engine in itself with the exception that all of the 30 units are in driving relation with an engine shaft common thereto. I have embodied my invention in a multiple cylinder engine employing a single rotary valving tube common to the cylinders thereof, this tube being provided with a plurality of pairs of ports each pair pertaining to an engine unit, the pairs of ports being distributed along the valving tube and co-operating with the engine cylinders to which they are individual 35 properly to regulate the admission of live gas to and the exhaustion of spent gas from the engine cylinders. In order that the exhaust ports of the tube may be kept out of communication with the admission ports in the tube a diaphragm is employed which separates the two classes of ports. As I have been able to embody my invention this diaphragm is straight throughout the major portion of its length, being deflected at its opposite ends to divide the tube into two separated chambers in order that free gas

and spent gas will not become intermixed in the valve tube.

I will explain my invention more fully by reference to the accompanying drawings 60 showing the preferred embodiment thereof and in which Fig. 1 is a view in elevation, partially in section, of an engine embodying the valving mechanism of my invention; Fig. 2 is a sectional view on line 2-2 of Fig. 1; 65 Figs. 3, 4, 5 and 6 are, respectively, sectional views of a part of the structure respectively taken on lines 3-3, 4-4, 5-5 and 6-6 of Fig. 1; Fig. 7 is an end view of a part of the engine as it is illustrated in Fig. 1; and 70 Fig. 8 is a view on a larger scale in side elevation, partially in section, of the engine showing the mechanism which is employed to secure quick action of the valving tube.

Like parts are indicated by similar characters of reference throughout the different figures.

The engine illustrated includes four engine units respectively having the cylinders 1, 2, 3 and 4, these cylinders respectively 80 having pistons 5, 6, 7 and 8 working therein. These pistons are suitably coupled with the engine shaft 9 by means of pitmen 10 and cranks 11 operating within a crank case 12 common to all of the engine units. The engine units are respectively provided with arcuate passages 13, 14, 15 and 16 which are out of communication with each other, being so arranged as to be limited to the cylinders of the engines to which they are 90 individual. The passages 13, 14, 15 and 16 have inner annular walls 17 and outer arcuate walls 18 suitably joined by end walls to complete the housing of said passages. Each passage is shown as opening directly 95 into the outer or upper end of the cylinder to which such passage is individual whereby fresh gas may be admitted to such cylinder or spent gas exhausted therefrom according to the adjustment of the valving mechanism that is to be described. Each arcuate wall portion 18 is surrounded by another arcuate wall portion 19 spaced apart therefrom whereby the space 20 is afforded 100 outside of the wall portions 18 within which cooling water may be forced to flow, this water being receivable through the pipe 21 that is provided for each water cooling space 20, the water passing into the continuation 22 of the corresponding passage 20 and being discharged through the continuation 23 of the passage 20. In this

22

manner the passages 13 etc. are cooled as is also the valving mechanism that is to be described. The inner and annular walls 17 of the passages 13 are desirably co-axial and 5 serve as bearings for the cylindrical rotary valving tube 24 in snug turning fit with said walls. The wall portions 17 and 18 pertaining to the different engine units may be joined by cylindrical portions 25 cast integrally therewith and also affording additional bearings for the valving tube 24, there being packing rings 26 for preventing the passage of gas between the engine units. There are also end extensions 27 of the 10 structure having the gas passages 13, etc., these end extensions also forming bearings for the rotary valving tube 24, there being packing rings 28 in these extensions 27 for preventing the outward passage of gas from 15 the end units of the engine. The fixed walls 17 of the gas passages 13, etc. are provided each with one port 29 for the admission of gas to or the exhaustion of gas from the corresponding engine unit. These ports 29 20 are distributed about the axis of the tube 24 so that in the four cylinder engine illustrated for example, gas may be passed into one cylinder, compressed in another, exploded in another and exhausted from the 25 remaining cylinder, all without the passage of gas from any one cylinder to another.

The valving mechanism for opening and closing the ports 29 in orderly sequence includes the aforesaid valving tube 24 having 30 formed therethrough a plurality of pairs of ports 31, 32, each pair being individual to a cylinder, the ports 31 being the exhaust ports and the ports 32 being the admission ports. Owing to the angular displacement 35 of the ports 29 in the stationary wall portions 17, all of the ports 31 may be aligned parallel with the axis of the tube 24 as may also all of the ports 32. The set of ports 31 are separated from the set of ports 32 by 40 means of the diaphragm or partition 33 which may be straight or in a single plane owing to the described relation of the ports 29 and which, in conjunction with the wall of the tube 24, divide the bore of this tube 45 into an exhaust passage 34 and an intake passage 35. Carburetted air or other gas is admitted through the pipe 36 and the ports 37 provided in the tube 24 to the intake passage 35. The exhaust passage 34 is in 50 communication with the outlet or exhaust pipe 38.

The engine illustrated is a four stroke per cycle engine. That is the piston of each engine unit operates to take in gas upon one 55 stroke of the piston, the intake stroke, (see Fig. 3 and piston 5 of Fig. 1); this same piston operates on a succeeding stroke, the compression stroke, to compress the gas taken in (see Fig. 6 and piston 8 in Fig. 1): 60 when this same piston operates on the third

stroke, the firing stroke, the compressed gas is exploded, there being suitable ignition means in each cylinder such as a spark plug 39 (see Fig. 4 and piston 6 of Fig. 1); and the piston operates on the fourth or scavenging stroke to exhaust the spent gas (see Fig. 5 and piston 7 of Fig. 1). When one of the intake ports 32 is in register with one of the ports 29 the remaining intake ports 32 are closed by the corresponding 70 walls 17 and at the same time one of the exhaust ports 31 is in register with another port 29, the remaining exhaust ports 31 being then closed. The valving tube 24 turns once during the four strokes of the engine 75 that occur in each cycle of operations, the tube turning step by step a quarter of a revolution per step. The quarter turns are preferably imparted to the valving tube very rapidly so that the admission and exhaust ports 32 and 31 will remain as long 80 as possible in register with the ports 29 to which the former ports are brought for respectively admitting and exhausting gas from some two of the cylinders and whereby as long a period as possible is afforded 85 in some third cylinder for compression and in some fourth cylinder for expansion. 90

The means employed for causing the periodic quarter turn movements of the valve tube 24 may preferably include a ratchet wheel 40 fixed upon and co-axial with the valving tube 24, an inwardly spring pressed holding dog 41 for engaging one of the four equidistant teeth of the ratchet wheel to hold the valving tube in the position to which it has been turned until it is to be turned again. There are four equidistant dog releasing cams 42, one individual to an engine cylinder, these cams being successively engageable with a cam element 43 upon the dog and operating successively, such operation occurring once upon each half turn of the engine shaft to release the dog 41 from engagement with the ratchet 100 wheel 40, and a ratchet turning spring 44 for moving the ratchet a quarter turn each time the dog 41 is released, the engaged cam 42 escaping engagement with the element 43 in time to permit the holding dog 41 to be inwardly 105 spring pressed into position to engage the ratchet tooth of the wheel 40 that succeeds the ratchet tooth from which the dog was previously removed by said cam. Since dog 41 must be returned by its spring in time to 110 engage the next tooth which swings quickly over to it, each cam 42 must be sufficiently short to drop element 43 immediately upon the release of wheel 40. The means for turning the cams 42 desirably resides in a 115 gear wheel 45 turning upon a bearing 46 which affords an axis of rotation for this gear wheel that is coincident with the axis of the valving tube 24, said gear wheel being rotatable with respect to said valving 120 125 130

tube in order that it may be kept in continuous rotation whether the valving tube is at rest or in motion. This gear wheel may be driven by a chain 47 that engages 5 its teeth and which, in turn, is driven by the gear wheel upon the shaft as indicated at the lower left hand portion of Fig. 1. One end of the spring 44 is anchored to the ratchet wheel 40 and the other end is anchored to the gear wheel 45 whereby the tension of this spring is increased by the engine rotated gear 45 during the period when the dog 41 is holding the ratchet 40. The anchorages of the spring turn with the parts 10 that carry them so that the spring is always in readiness to function irrespective of the positions to which the anchorages have been placed.

By the construction described the admission and exhaust ports 32 and 31 are closely approached enabling the employment of short movements of the valving tube 24, the quarter turn movements, which have been described, a feature which is of importance 25 since it is desirable to have sharp movements of a rotating body to extend over as short distances as possible, a characteristic which is particularly desirable in my valving mechanism since the ports may be very 30 quickly opened and closed. By this mechanism back pressure is instantly relieved upon the opening of the exhaust ports and wide passage for the flow of gas through the admission ports is instantly afforded by the 35 opening of these admission ports.

Other objects and advantages in the engine of my design will be readily appreciated by those skilled in the art. It is also obvious that many characteristics of my invention 40 may be employed in a single engine unit, that is an engine having but a single cylinder with its piston.

While I have herein shown and particularly described the preferred embodiment 45 of my invention I do not wish to be limited to the precise details of construction shown as changes may readily be made without departing from the spirit of my invention, but having thus described my invention I claim 50 as new and desire to secure by Letters Patent the following:—

1. An internal combustion engine including a cylinder; a piston operating in the cylinder; a valving tube having separate 55 passages for the admission and exhaustion of engine operating fluid and formed with admission and exhaust ports respectively communicating with these passages; a wall having a port in communication with the cylinder and alternately closing said admission and exhaust ports; a spring connected at one end with the valving tube and operating to turn it; an engine rotated element with which the other end of the spring 60 is connected; means adapted to hold the

valving tube in successive positions against the force of said spring; and intermittently operating engine operated means for periodically releasing said holding means.

2. An internal combustion engine including a cylinder; a piston operating in the cylinder; a valving tube having separate 70 passages for the admission and exhaustion of engine operating fluid and formed with admission and exhaust ports respectively communicating with these passages; a wall having a port in communication with the cylinder and alternately closing said admission and exhaust ports; a ratchet wheel secured to the valving tube; a spring connected at one end with the ratchet wheel and operating to turn it; an engine rotated element with which the other end of the spring 75 is connected; a dog adapted for holding engagement with teeth of the ratchet wheel to hold the valving tube in successive positions against the force of said spring; and intermittently operating engine operated means periodically releasing said holding dog to permit the spring to function.

3. An internal combustion engine including a cylinder; a piston operating in the cylinder; a valving tube having separate 80 passages for the admission and exhaustion of engine operating fluid and formed with admission and exhaust ports respectively communicating with these passages; a wall having a port in communication with the cylinder and alternately closing said admission and exhaust ports; a ratchet wheel secured to the valving tube; a spring connected at one end with the ratchet wheel and operating to turn it; an engine rotated element with which the other end of the spring 85 is connected; a dog adapted for holding engagement with teeth of the ratchet wheel to hold the valving tube in successive positions against the force of said spring; and intermittently operating engine operated means periodically releasing said holding dog to permit the spring to function.

4. An internal combustion engine including a number of units each employing a cylinder; a piston operating in the cylinder; a valving tube having separate 90

passages for the admission and exhaustion of engine operating fluid and formed with admission and exhaust ports for each unit respectively communicating with these passages, the admission ports in the valving tube being aligned substantially parallel with the tube axis in the aforesaid admission passage and the exhaust ports being aligned substantially parallel with the tube axis in the exhaust passage; a wall having ports, one for each engine unit, in communication with the cylinder of such unit and alternately closing those of said admission and exhaust 95 ports pertaining to such unit, the ports in 100

110

115

120

125

130

said wall being angularly displaced with respect to each other; and mechanism for intermittently turning said valving tube parts of a revolution with respect to said wall.

5. An internal combustion engine including a number of units each employing a cylinder; a piston operating in the cylinder; a valving tube having separate passages for 10 the admission and exhaustion of engine operating fluid and formed with admission and exhaust ports for each unit respectively communicating with these passages, the admission ports in the valving tube being 15 aligned substantially parallel with the tube axis in the aforesaid admission passage and the exhaust ports being aligned substantially parallel with the tube axis in the exhaust passage; a wall having ports, one for 20 each engine unit, in communication with the cylinder of such unit and alternately closing those of said admission and exhaust ports pertaining to such unit, the ports in 25 said wall being angularly displaced with respect to each other; a spring connected at one end with the valving tube and operating to turn it; an engine rotated element with which the other end of the spring is 30 connected; means adapted to hold the valving tube in successive positions against the force of said spring; and intermittently operating engine operated means periodically releasing said holding means.

6. An internal combustion engine including a number of units each employing a cylinder; a piston operating in the cylinder; a valving tube having separate passages for 35 the admission and exhaustion of engine operating fluid and formed with admission and exhaust ports for each unit respectively communicating with these passages, the admission ports in the valving tube being aligned substantially parallel with the tube axis in the aforesaid admission passage and the exhaust ports being aligned substantially parallel with the tube axis in the exhaust passage; a wall having ports, one for 40 each engine unit, in communication with the cylinder of such unit and alternately closing those of said admission and exhaust ports pertaining to such unit, the ports in 45 said wall being angularly displaced with respect to each other; a ratchet wheel secured to the valving tube; a spring connected at one end with the ratchet wheel and operating to turn it; an engine rotated element with which the other end of the spring is 50 connected; a dog adapted for holding engagement with teeth of the ratchet wheel to hold the valving tube in successive 55 positions against the force of said spring; and intermittently operating engine operated means for periodically releasing said holding dog to permit the spring to function.

ports pertaining to such unit, the ports in said wall being angularly displaced with respect to each other; a ratchet wheel secured to the valving tube; a spring connected at one end with the ratchet wheel and operating to turn it; an engine rotated element with which the other end of the spring is connected; a dog adapted for holding engagement with teeth of the ratchet wheel to hold the valving tube in successive 60 positions against the force of said spring; and intermittently operating engine operated means for periodically releasing said holding dog to permit the spring to function.

7. An internal combustion engine including a number of units each employing a cylinder; a piston operating in the cylinder; a valving tube having separate passages for 65 the admission and exhaustion of engine operating fluid and formed with admission and exhaust ports for each unit respectively communicating with these passages, the admission ports in the valving tube being aligned substantially parallel with the tube axis in the aforesaid admission passage and the exhaust ports being aligned substantially parallel with the tube axis in the exhaust passage; a wall having ports, one for 70 each engine unit, in communication with the cylinder of such unit and alternately closing those of said admission and exhaust ports pertaining to such unit, the ports in 75 said wall being angularly displaced with respect to each other; a ratchet wheel secured to the valving tube; a spring connected at one end with the ratchet wheel and operating to turn it; an engine rotated element with which the other end of the spring is connected; a dog adapted for holding engagement with teeth of the ratchet wheel to hold the valving tube in successive 80 positions against the force of said spring; and a cam operated by said engine rotated element and periodically having releasing engagement with said dog to permit the 85 spring to function.

In witness whereof, I hereunto subscribe my name this 13th day of Dec. A. D., 1919.

HARRY A. DOUGLAS.
